US00D982180S

(12) **United States Design Patent** (10) **Patent No.:** **US D982,180 S**
(45) **Date of Patent:** **** Mar. 28, 2023**

(54) **CAP FOR LIGHT EMITTING DEVICE**

(71) Applicant: **LUMENIS LTD.**, Yokneam (IL)

(72) Inventors: **Hernan Altman**, Kiryat Tivon (IL);
Joseph Birman, Haifa (IL)

(73) Assignee: **LUMENIS BE LTD.**, Yokneam (IL)

(**) Term: **15 Years**

(21) Appl. No.: **29/764,416**

(22) Filed: **Dec. 30, 2020**

(51) **LOC (14) Cl.** **24-99**

(52) **U.S. Cl.**

USPC **D24/231**

(58) **Field of Classification Search**

USPC D24/108, 111, 112, 127, 129, 130, 164,

(57) **CLAIM**

The ornamental design for a cap for light emitting device, as shown and described.

DESCRIPTION

FIG. 1 is a Top Perspective View of the new design.

FIG. 2 is a Bottom Perspective View of the new design.

FIG. 3 is a Left View of the new design.

FIG. 4 is a Right-Side View of the new design.

FIG. 5 is a Front View of the new design.

FIG. 6 is a Rear View of the new design.

FIG. 7 is a Top View of the new design; and,

FIG. 8 is a Bottom View of the new design.

1 Claim, 8 Drawing Sheets
